UNITED STATES PATENT OFFICE.

THOMAS F. TOMLINSON, OF LAMBERTS POINT, VIRGINIA.

BRAKE-RIGGING FOR ROLLING-STOCK.

1,218,720.

Specification of Letters Patent. Patented Mar. 13, 1917.

Application filed May 9, 1916. Serial No. 96,416.

To all whom it may concern:

Be it known that I, THOMAS F. TOMLINSON, a citizen of the United States, residing at Lamberts Point, in the county of Norfolk and State of Virginia, have invented certain new and useful Improvements in Brake-Rigging for Rolling-Stock, of which the following is a specification.

This invention relates to brake rigging for rolling stock, the principal object being to provide an equally efficient braking mechanism under varying conditions.

Another object is to provide interchangeable levers which operate in conjunction with complementally reversible brake shoes, to provide a means for equalizing the wear on brake shoes, and permitting variation, should any part be rendered unsuitable for use.

Still another object of the invention is to use a brake rigging which is engageable with the upper terminals of said interchangeable levers, and which is changeable to accord with the change of said levers for applying the brakes.

A further object of the invention is to provide a braking mechanism which is operable by the usual atmospherical source of energy, although suitable means are provided for manually applying the brakes when so desired.

Still another object resides in the peculiar, yet simple arrangement of parts, by which the wheels may be locked from any movement whatsoever if desired, without necessitating the expenditure of more energy than is used in current air brake system, or without subjecting the parts to undue strain.

Other objects as well as the nature, characteristic features and scope of my invention will be more readily understood from the following description taken in connection with the accompanying drawings and pointed out in the claims forming a part of this specification.

Referring to the drawings:

Figure 1 is a top plan view of a brake rigging constructed in accordance with my invention, a portion thereof being broken away, the rigging being applied to a car truck, the latter being shown in dotted lines;

Fig. 2 is a cross sectional view on the same;

Fig. 3 is a top plan enlarged view of a

portion of the brake rigging shown in Fig. 1, showing one of the levers, after pressure has been exerted thereon;

Fig. 4 is a cross sectional view of a portion of a car truck embodying a modification of my brake rigging, and more specially of the brake shoe supporting levers;

Fig. 5 is a perspective view of one of the shoe frames used in this invention;

Fig. 6 is a plan view of a portion of one of the detachable bolster engaging shoe supporting brackets used in the invention, showing a modified form over that illustrated in Figs. 1, 2 and 4;

Fig. 7 is a cross sectional view of the bracket *per se*;

Fig. 8 is a top plan view of two modified forms of my invention illustrating the application of the same on a car truck equipped with braking levers as shown in Figs. 2 and 4;

Fig. 9 is a plan view of another pair of modified brake operating means, illustrating cables for use in the cap city of the levers shown in Fig. 8;

Fig. 10 is a side elevational view of one of the hangers and pulley housing used in the present invention,

Fig. 11 is a cross sectional view of the hangers shown in Fig. 8, to which an equalizing beam is pivoted.

Fig. 12 is a detail fragmentary bottom plan view, partly in section, of my invention, showing to advantage the connection between one of the side frames and shoe supporting lever brackets.

In the drawings a detail description of Figs. 1, 2 and 3 will first be given in order that a clear understanding may be had of this form of the invention, in contradistinction to the forms shown in the other views. In this form of the invention a body plate 1 is provided which in this instance is of a substantially oblong configuration, one end thereof being bifurcated and having the branches of the bifurcation twisted into substantially parallel relation with the longitudinal axis of the body, providing spaced ears 2, which are adapted to receive the upper free terminals of the brake supporting levers 3 therebetween. Portions on the opposite sides of said ears 2 are extended and reversely folded upon themselves to provide elongated loops 4, which are adapted for pivotal engagement with a rockable lever 5.

forming a part of the brake rigging, as illustrated to advantage in Fig. 3. The opposite end of the body 1 is also bifurcated so as to provide an elongated slot 6 therein in which 5 the upper terminal of one of the brake supporting levers 3 is mounted for movement. It will be noted thus far that the levers which are mounted between the ears 2 and in the elongated slot 6 are associated with 10 different brake shoes, and are adapted for movement in either coincident or counter-direction therein as will be more fully hereinafter set forth. A floating bar 7 is superposed upon each of the body bars 1, one end 15 of each of said floating bars being bifurcated as indicated at 8 for pivotal connection with the upper terminal of one of the shoe supporting levers 3, while an incision is formed along the longitudinal axis of the opposite 20 end, permitting said ends to be folded one over the other as at 9, for pivotal engagement with the rockable lever 5. It will be noted that an aperture 10 is arranged in the free terminal of the lever 5, which is 25 adapted for alinement with openings 11 in the loop portions 4 of said body plate 1, whereby the fulcrum point of said lever 5 may be shifted, when it is desired to change the direction of movement of the brake shoe 30 supporting levers 3 and 15.

The means by which pressure is exerted upon the rockable levers 5, consists of parallelly arranged bars 12, one end of each of which is pivotally engaged with one of the 35 levers 5, while the opposite end of each is in pivotal engagement with an equalizing beam 13, the latter being pivotally engaged, approximately midway its end, with a power rod 14 as shown in Fig. 1. The power rod 40 14 is of course engaged with a source of energy in the usual or any desired manner.

The lower ends of the brake supporting levers are extended and have the terminals thereof enlarged to provide shoes 3' for engagement with the track over which the 45 wheels of the rolling stock pass.

In operation, it is understood that as soon as pressure is exerted upon the power rod 50 14, that motion will be intercommunicated to the shoe supporting levers 3, which will throw the brake shoes 19 in counterdirections for snug engagement with the peripheries of the truck wheels. The rail engaging shoes 3' will, of course, be simultaneously engaged with the rail track, thereby 55 obtaining a positive braking action.

In Fig. 4 a precise construction to that shown in Figs. 1, 2 and 3 is illustrated, with the exception that instead of using the brake supporting levers 3, a varying form is illustrated, which is indicated in Fig. 4 at 15. The levers shown in this view are of an arcuate configuration, conforming substantially to the contour of the car wheel, having 60 their inner terminals enlarged so as to

provide reinforced ends for pivotal engagement with the ears 16 of the brake shoe frame 17. The levers 15 are pivotally engaged with a bracket 23 which is also of a form variant to that shown in Figs. 1, 2 and 3. However it will be found that best results are obtained if different species of brackets are used, consistent with the desired positioning of the levers 3 in Figs. 1, 2 and 3, and levers 15 in Fig. 4.

It will be noted therefore that in Fig. 2 the shoes are operated by exerting pressure on the levers 3 in counterdirections, whereas in Fig. 4 the brake shoes are applied by moving said levers toward each other.

Each of the brake shoe frames 17 is of an arcuate configuration and is provided with a pair of parallelly arranged apertured ribs 18 which extend transversely of the frame, approximately midway its end, for pivotal engagement with a complementary ear on the back of the brake shoe 19. The opposite ends of said frame are provided with side flanges 20 which co-act with corresponding ribs 21 on the backs of said shoes 19, in order to prevent casual displacement of the latter, for insuring a positive braking action at all times. By the peculiar formation shown however it will be appreciated that the shoes 19 may be readily removed when so desired, so as to permit substitution of new ones therefor. The shoes 19 are provided with abutments 22 on their opposite terminals, in order to prevent vertical movement of the same.

Fig. 12 illustrates to advantage the connection between one of the side frames and brackets which supports the shoe supporting levers. In this instance a portion of one side frame 53 is shown, upon which the bracket 23 is integrally formed. Portions of the bracket are extended laterally to provide the ears 24.

Inasmuch as a specific form of truck bolster, and brake shoe supporting lever bracket 54 has been shown in Figs. 1, 2 and 4 of the drawings, I have in Figs. 6 and 7 shown a type of brake lever supporting bracket which is adaptable for use with standard types of bolsters or spring planks, which may be expeditiously associated therewith when desired. A bracket is indicated at 23 and in this instance is of a U-shape configuration, for engagement with the outer face of the spring plank 23', the application of which is illustrated in Fig. 6. Ears 24 extend laterally from said bracket and are adapted for pivotal engagement with the shoe supporting levers in either the form as shown in Figs. 1 and 2, or as that shown in Fig. 4.

Fig. 8 discloses two different forms of brake rigging, one of which is associated with the brake shoes on one side of the truck, while the other is associated with the brake shoes on the other side of the truck. Re-

ferring primarily to that form shown on the left side, it will be noted that hangers 25 are provided, which are adapted to be pendently supported by the car body in the usual manner, certain of which are adapted for pivotal engagement with certain of the equalizing beams, one of which is indicated at 26 on the left side of the view shown in Fig. 8. Other of said beams are adapted to be floatingly arranged in certain of said hangers, one being shown on the left side of Fig. 8 and indicated at 27. The brake shoes and brake supporting levers are associated with the spring plank, the same as shown in either Figs. 1, 2 or 4, the shoe supporting levers being indicated in this instance at 28, in order that the drawings may be comprehensively understood. An elongated rod 29 extends from the pivoted equalizer beam 26 to the floating beam 27, being equipped in its opposite end with eyes for pivotal engagement in complementary openings on the inner terminals of said beams 26 and 27. The outer terminal of each of said beams is adapted for movable engagement with one end of a link 30, the opposite end of each of said links being provided with an enlarged eye 31, which is movably engaged with the upper terminal of a lever 28. From this construction it will be appreciated that as soon as pressure is exerted upon the floating beam 27, that motion will be imparted, in counterdirection, to the levers 28, so that this construction of rigging would be especially adaptable for use in connection with the form of brake supporting lever as shown in Figs. 1 and 2.

The form shown on the right side of Fig. 8 embodies exactly the same construction, as regards the hangers and beams, as that shown on the left side of the drawings.

Variation in the rods, or levers is made inasmuch as two rods 32 are used in the place of the one rod 29, each of said rods 32 being provided with inner threaded terminals 33 which carry a turn buckle 34 thereon, whereby said rods 32 may be adjusted. The outer terminals of said rods 32 are adjustably mounted in apertured supporting links 35, the latter being in turn pivotally engaged with the pivoted and floating beams. This construction will permit of a double adjustment of the rods 32, since they may be moved by turning the turn buckle 34, or by changing the position of the outer ends of said rods which engage the apertures of the members 35. In this form rods 36 supplant the rods 30 and are relatively longer than the latter, since each of the rods 36 is adapted to engage the brake lever which is the farther spaced from the beam to which the rod is secured. In use of this form it will seem that the exertion of pressure upon the floating beam 65 will impart movement to the rods 36 so

as to operate the two supporting levers in a direction toward each other, this form being especially adapted for use with the type of lever shown in Fig. 4 of the drawings.

A main equalizing beam 37 is floatingly mounted in hangers 38, the opposite ends thereof being in connection with the floating beams of the brake rigging shown on both the right and left hand sides of Fig. 8, whereby motion will be simultaneously imparted to said auxiliary floating beams, when pressure is exerted upon the main beam 37. A power bar 39 is in operative connection with the main beam 37, one end thereof being pivotally mounted in a hanger 40 while the opposite end is movable in a horizontal arc, from an atmospherical source of energy, in this instance being in connection with a piston rod 41. It is therefore seen that the brakes may be applied, if desired, in the usual manner, by the use of the air brake system now used, or if desired may be operated mechanically, by placing a chain 42 in connection with a suitable hand wheel, etc. It will likewise be noted that the manual means is entirely independent of the atmospherical means of applying the brakes, so that one can be operated, independently of the other, whereby application of the brakes will at all times be insured.

If desired, the parts 1, 5, 7, 12 and 14, as shown in Figs. 1 to 4, may be removed and replaced by either form of rigging as shown in Fig. 8, to harmonize with the change of the brake shoe lever fulcrum. Different species of rigging may in this way be used for different classes of work, with the same sum total result.

In Fig. 9 I have shown a form of invention which simulates the construction shown in Fig. 8, and differs therefrom only in construction, but not in mode of operation and subsequent results. In Fig. 9, I have on the left side of this view shown a hanger 43, which is adapted to be supported by the car body, and in which is journaled a pulley wheel 44. A second hanger as indicated at 45 is provided, which is spaced from the hanger 43 and off-set therefrom, said hanger 45 having pivotally mounted thereon, one end of a supporting arm 46, the opposite end being bifurcated and having mounted between the branches of the bifurcation, a pulley wheel 47. Pulley wheels 47 are provided with the usual concaved outer periphery, and have trained thereabout a cable 48, the opposite ends of which are provided with rings 49, which in turn are pivotally engaged with the upper terminals of the shoe supporting levers 50 as shown in dotted lines.

The construction shown in the right hand side of this view is identical with that

shown in the left side, with the exception that the cable, as indicated in this view at 51, is extended and has the opposite ends thereof crossed for engagement with the brake supporting levers which are farthest remote from the pulley wheel, about which its respective cable engaging end has been passed.

In the operation of this form pressure is exerted upon the arms 46, which movement will bodily actuate the pulley wheels 47 thereof, so as to exert pressure upon the cables 48 and 51, consequently operating the brake levers.

15 It will be understood that the above description and accompanying drawings comprehend only the general and preferred embodiment of my invention, and that various minor changes in details of construction, 20 proportion and arrangement of parts may be made within the scope of the appended claims without sacrificing any of the advantages of my invention.

Having thus fully described my invention, 25 what I claim as new and desire to secure by Letters Patent, is:—

1. A brake rigging for rolling stock including brake shoe supporting levers, the fulcrum points of said levers being changeable to vary the strain on said shoes, and mechanism engaged with said levers to operate the latter, the fulcrum point of said mechanism being changeable to accord with the change of levers for positively applying 35 the brakes.

2. A brake rigging in combination with brake shoes, levers in connection with said shoes to operate the latter, and means common to all of said levers for simultaneously exerting pressure on said shoes, the points of connection between said shoes and said levers being interchangeable, to permit operation of the levers toward or away from each other for applying the brakes.

45 3. A brake rigging for rolling stock including brake shoe supporting levers pivotally carried by the rolling stock and equipped with shoes, the fulcrum points of said levers

being changeable to permit the upper terminals of said levers to be moved toward or away from each other for applying the brakes, and means connected to the upper terminals of said levers and changeable to accord with the change of the fulcrum points of the levers, substantially as set forth.

4. A car brake mechanism including, in combination with shoe supporting levers, a body bar for association with a pair of said levers on one side of the car, one of said levers being fixedly connected with said bar, to operate simultaneously therewith, the other lever being independently movable of said bar, a floating bar carried by the body bar and being in connection with said independently movable lever to operate the latter, means pivotally engaged with said body bar and floating bar, said shoe supporting levers being simultaneously operable by the exertion of pressure upon said means to apply the brakes.

5. A car brake operating mechanism including, in combination with brake shoe supporting levers, a body bar for association with a pair of the levers on one side of the car, one end of said bar being fixedly engaged with one of said levers, whereby the latter is moved simultaneously with the movement of said bar, the opposite end of said bar being slidably engaged with the opposite lever to provide a guide, a floating bar, one end of which is in engagement with said lever which is slidably movable with the body bar, a floating lever, one end of which is in pivotal engagement with said floating bar and with one side of said body bar, whereby exertion of pressure upon said floating lever operates said brake supporting levers in opposite directions.

In testimony whereof I affix my signature in presence of two witnesses.

THOMAS F. TOMLINSON.
